UNITED STATES PATENT OFFICE.

CHARLES H. HAUPT, OF ELIZABETH, NEW JERSEY, ASSIGNOR, BY MESNE ASSIGNMENTS, TO STANDARD DEVELOPMENT COMPANY, OF NEW YORK, N. Y., A CORPORATION OF DELAWARE.

TANK-CAR-OUTLET VALVE.

Application filed January 12, 1921. Serial No. 436,820.

To all whom it may concern:

Be it known that I, CHARLES H. HAUPT, a citizen of the United States, residing at 777 Salem Avenue, Elizabeth, in the county of 5 Union and State of New Jersey, have invented a new and useful Improvement in Tank-Car-Outlet Valves, of which the following is a specification.

The present invention relates to tank car outlet valves and more particularly to devices in connection therewith whereby the opened or closed condition of the valve is indicated, and the application of the cap or closure to the outlet is prevented when the 15 valve is open. The invention will be fully understood from the following description thereof, illustrated by the accompanying drawing, in which—

Figure 1 is a vertical sectional view 20 through an outlet valve construction embodying the invention, and

Figure 2 is a vertical sectional view 25 through a modified form of construction.

Referring more particularly to Fig. 1 of 30 the drawing, the numeral 5 indicates the bottom of a car tank, provided at 6 with an outlet opening. Below the outlet opening an outlet nozzle 7 is secured externally to the bottom of the tank, by rivets, bolts or other suitable devices. A reciprocable valve 35 8, which is operated by means of a rod 9 (shown broken away) extending upwardly to the top of the tank, seats upon the upper internal edge 9 of the nozzle 7. A rod 10 projects downwardly from the valve 8 into the nozzle 7, being secured to the valve in any suitable manner. As shown, the rod 10 is provided with a head 11 which fits within a threaded recess 12 formed in the bottom 40 of the valve and is held in position by the annular threaded ring 13. The rod may be guided by the central opening in a spider 14 secured within the nozzle 7. At its lower end the rod 10 is secured to the movable 45 pivot pin 15, which may suitably pass through an eye in the end of the rod 10 and which pivot pin serves as a connection for the series of toggle links 16, 16, 16 connected together in pantograph fashion and 50 having a fixed pivot upon the pin 17 which extends horizontally through the nozzle. The lower ends 18, 18, of the toggle links are substantially aligned with the bottom of the nozzle when the valve is seated and upon

raising the valve are projected downwardly 55 from the nozzle. The lower portion of the nozzle is provided with screw threads 19, whereby a suitable cap or closure may be secured thereto.

It is readily apparent that with the construction described the position of the ends 60 18, 18 of the toggle ends clearly indicates the position of the valve and furthermore prevents the application of the closure or cap to the nozzle except when the valve is 65 closed or seated. It is likewise apparent that when the valve is closed and the cap or closure applied to the nozzle, the toggle ends are held by the cap in such position as to lock the valve upon its seat.

In the form of construction shown in Fig. 2 the numeral 20 indicates the nozzle secured below the outlet opening of the tank car bottom 21, the numeral 22 indicating the reciprocable valve adapted to close the outlet. This valve is provided as in the construction of Fig. 1 with a downwardly projecting rod 23 passing through an opening in the spider 24 secured within the nozzle 20. In the lower portion of the nozzle a 70 80 lever 25 is pivotally mounted upon the pin 26 secured to the nozzle and a link 27 connects the end of the rod 23 with one end of the lever 25. To the free end of the lever 25 a loosely pivoted pendant member 28 is 85 secured. The bottom of the nozzle is threaded as at 29 for the application of a suitable cap. In this form of construction the position of the free end of the lever 25 and of the pendant 28 secured thereto indicates the 90 corresponding position of the valve and prevents application of the closure when the valve is open. The lever likewise acts to lock the valve on its seat when the cap or closure is applied to the nozzle.

Although the present invention has been described in connection with the specific details of forms of construction embodying the same, it is not intended that the details of the forms of constructions described are 100 to be regarded as limitations upon the scope of the invention except insofar as included in the accompanying claims.

I claim:

1. In a tank car outlet, a nozzle projecting from the tank, a reciprocable valve adapted to close the outlet from within the tank and means within the nozzle operated

2
1,439,415

- by the movement of the valve, said means being projected from the nozzle when the valve is raised from its seat and being retracted thereinto when the valve is seated.
- 5 2. In a tank car outlet, a nozzle projecting from the tank, a reciprocable valve adapted to close the outlet from within the tank and means within the nozzle and operatively connected to the valve and projecting from the nozzle when the valve is raised from its seat and being retracted thereinto when the valve is seated, said means being locked within the nozzle when a closure is applied thereto.
- 15 3. In a tank car outlet, a nozzle projecting from the tank, a reciprocable valve adapted to close the outlet from within the tank, a member pivotally mounted within the nozzle, a rod secured to the valve and operatively connected to said pivotally mounted member, whereby the said member is projected from the nozzle when the valve is raised from its seat and is retracted within the nozzle when the valve is closed.
4. In a tank car outlet, an outwardly projecting nozzle, a reciprocable valve adapted to close the outlet from within the tank, a rod secured to the valve, a lever pivotally mounted within the nozzle and a connecting link between the rod and one end of the lever whereby on raising the valve from its seat the free end of the lever is projected from the nozzle and on seating the valve it is retracted within the nozzle.
5. In a tank car outlet, an outwardly projecting nozzle, a reciprocable valve adapted to close the outlet from within the tank, a rod secured to the valve, a lever pivotally mounted within the nozzle, a connecting link between the rod and one end of the lever whereby on raising the valve from its seat the free end of the lever is projected from the nozzle and on seating the valve it is retracted within the nozzle, and a pendant member pivotally secured to the free end of the lever.

CHARLES H. HAUPT.
